UNITED STATES PATENT OFFICE.

PHILIP D. HIBNER, OF SEATTLE, WASHINGTON.

INTERNAL-COMBUSTION ENGINE.

1,342,108.

Specification of Letters Patent.

Patented June 1, 1920.

Application filed April 10, 1919. Serial No. 288,950.

To all whom it may concern:

Be it known that I, PHILIP D. HIBNER, a citizen of the United States, and resident of the city of Seattle, county of King, and

5 State of Washington, have invented a new and useful Improvement in Internal-Combustion Engines, of which the following is a specification.

The object of my invention is to provide 10 novel means for producing a compressed combustible gas by forcing compressed air and liquid fuel through a mixer and vaporizer and for supplying the compressed combustible gas to an internal combustion 15 engine, means also being employed to supply compressed air to the engine for starting the same and for scavenging and cooling the engine cylinders.

The object of my invention more particularly is to provide certain improvements 20 in charge forming devices whereby the liquid fuel and air are forced through a suitable mixer and vaporizer and the resulting compressed combustible gas is forced from 25 the mixer and vaporizer into a reservoir from which the engine is supplied; means controlled by the rise and fall in the pressure of the combustible gas being employed for closing and opening the supply of compressed air and liquid fuel to the mixer and 30 vaporizer; and means being employed for opening to a greater or lesser degree the supply of compressed combustible fuel or compressed air or both to the engine, the 35 cycle of operations of the engine being controlled by its own valves designed to alternately admit the compressed combustible gas and compressed air.

A practical embodiment of my invention 40 is represented diagrammatically in the accompanying drawings.

The internal combustion engine 1 may be of the rotary type, its valve chests being denoted by 2. The air pump 3 is driven 45 from the shaft 4 of the engine and forces compressed air into the reservoir 5 through the line 6. Compressed air is supplied to the fuel reservoir 7 through the line 8 which line may have a reducing valve 9 therein.

50 A liquid fuel supply line 10 leads from the reservoir 7 to the mixer and vaporizer 11. A compressed air supply line 12 leads from the compressed air reservoir 5 also to the mixer and vaporizer 11. Means may 55 be provided for heating the compressed air as it leads from the reservoir 5 to the mixer

and vaporizer, such means being herein denoted by a heater 13 located in the exhaust line 14 of the engine and surrounding coils in the compressed air supply line. 60

A compressed air and liquid fuel controlling valve 15 is located in the supply lines 12 and 10. A compressed combustible gas supply line 16 leads from the mixer and vaporizer 11 to the compressed combustible 65 gas reservoir 17, in which line is located a check valve 18.

A branch line 19 leads from the compressed combustible gas line 16 to the controlling valve 15, whereby the valve is operated to close and open the compressed air and liquid fuel supply lines to the mixer and vaporizer as the pressure in the combustible gas reservoir rises and falls to predetermined points. 70

A drain line 20 leads from the bottom of the compressed combustible gas reservoir 17 to the top of the liquid fuel reservoir 7 in which line is located a drain cock 21 whereby any liquid fuel which is deposited in the 80 compressed combustible gas reservoir may be drained at suitable times into the liquid fuel reservoir. A compressed combustible gas supply line 22 with its branches leads to the valve chests 2 of the engine through a manually operated throttle valve 23. 85

A compressed air supply line 24 with its branches also leads to the valve chests 2 through the manually operated throttle valve 23. 90

A cut out valve 25 may be provided in the engine exhaust line 14 for controlling the passage of the products of combustion to the heater 13.

The mixer and vaporizer 11 may be like 95 the one represented in my application filed January 27, 1919, Serial No. 273365, and the compressed air and liquid fuel controlling valve 15 may be like the one represented in my application filed January 18, 1919, Serial No. 271857. 100

The throttle valve 23 may be like the one represented in my application filed January 28, 1919, Serial No. 273627, and the internal combustion engine may be like the 105 one represented in my application filed March 11, 1919, Serial No. 281953.

The air pump may be like the one represented in my United States Letters Patent No. 1242692 dated October 9, 1919. 110

In operation and presupposing the reservoir 5 to have a supply of compressed air and

the reservoir 7 to have a supply of liquid fuel; the throttle valve 23 is turned to a position which will supply compressed air only to the valve chests 2 of the engine, thereby 5 starting the engine and the air pump. After the engine and pump have been started, the throttle valve 23 is turned into a position to supply both the compressed combustible gas and the compressed air to 10 the said valve chests, the valves therein being operated to alternately supply the compressed combustible gas and the compressed air to the engine, whereby the engine is cooled and scavenged after each combustion, thus reducing the temperature of the combustion chambers and by the complete 15 elimination of the burned gases, materially increasing the efficiency of the engine.

The compressed air and liquid fuel supply 20 controlling valve 15 is operated by a rise or fall in the pressure of the combustible gas in the reservoir 7 to close or open the compressed air and liquid fuel supply lines to the mixer and vaporizer, thus automatically 25 maintaining the combustible gas at substantially a predetermined pressure.

The system as above described is very effective in the production of an efficient fuel and in the supercharging and scavenging of 30 the engine, the arrangement of the parts being very simple and their operation automatic after the engine is started.

What I claim is:

1. In combination, an internal combustion 35 engine, a mixer and vaporizer, pressure means for forcing the air and liquid fuel therethrough and in the form of a compressed combustible gas to the engine and a valve controlled by the rise and fall of the 40 combustible gas pressure for closing and opening the supply of air and liquid fuel to the mixer and vaporizer.

2. In combination, an internal combustion 45 engine, a mixer and vaporizer, pressure means for forcing the air and liquid fuel therethrough and in the form of a compressed combustible gas to the engine and a throttle valve for regulating the supply of compressed air and combustible gas, one or 50 both, to the engine.

3. In combination, an internal combustion 55 engine, a mixer and vaporizer, pressure means for forcing the air and liquid fuel therethrough and in the form of a compressed combustible gas to the engine, a valve controlled by the rise and fall of the combustible gas pressure for closing and opening the supply of air and liquid fuel to the mixer and vaporizer, and a throttle valve 60 for regulating the supply of compressed air and combustible gas, one or both, to the engine.

4. In combination, an internal combustion 65 engine, a mixer and vaporizer, a gas reservoir, pressure means for forcing air and

liquid fuel through the mixer and vaporizer and in the form of a compressed combustible gas to the reservoir and a valve controlled by the rise and fall of the combustible gas pressure for closing and opening the supply 70 of air and liquid fuel to the mixer and vaporizer.

5. In combination, an internal combustion engine, a mixer and vaporizer, a gas reservoir, pressure means for forcing air and 75 liquid fuel through the mixer and vaporizer and in the form of a compressed combustible gas to the reservoir and a throttle valve for regulating the supply of compressed air and combustible gas, one or both, to the engine. 80

6. In combination, an internal combustion engine, a mixer and vaporizer, a gas reservoir, pressure means for forcing air and liquid fuel through the mixer and vaporizer and in the form of a compressed combustible 85 gas to the reservoir, a valve controlled by the rise and fall of the combustible gas pressure for closing and opening the supply of air and liquid fuel to the mixer and vaporizer, and a throttle valve for regulating the supply 90 of compressed air and combustible gas, one or both, to the engine.

7. In combination, an internal combustion engine, its valve chests, an air and liquid fuel mixer and vaporizer, compressed air, 95 liquid fuel, and combustible gas reservoirs, supply lines leading from the compressed air and liquid fuel reservoirs to the mixer and vaporizer; from the compressed air and combustible gas reservoirs to the valve chests 100 and from the mixer and vaporizer to the combustible gas reservoir.

8. In combination, an internal combustion engine, an air and liquid fuel mixer and vaporizer, compressed air, liquid fuel, and 105 combustible gas reservoirs, supply lines leading from the compressed air and liquid fuel reservoirs to the mixer and vaporizer; from the compressed air and combustible gas reservoirs to the engine, and from the 110 mixer and vaporizer to the combustible gas reservoir and a valve controlled by the rise and fall of the combustible gas pressure for closing and opening the supply of air and liquid fuel to the mixer and vaporizer. 115

9. In combination, an internal combustion engine, an air and liquid fuel mixer and vaporizer, compressed air, liquid fuel, and combustible gas reservoirs, supply lines leading from the compressed air and liquid 120 fuel reservoirs to the mixer and vaporizer; from the compressed air and combustible gas reservoirs to the engine, and from the mixer and vaporizer to the combustible gas reservoir and a throttle valve for regulating 125 the supply of compressed air and combustible gas, one or both, to the engine.

10. In combination, an internal combustion engine, an air and liquid fuel mixer and vaporizer, compressed air, liquid fuel, 130

and combustible gas reservoirs, supply lines leading from the compressed air and liquid fuel reservoirs to the mixer and vaporizer; from the compressed air and combustible

5 gas reservoirs to the engine, and from the mixer and vaporizer to the combustible gas reservoir, a valve controlled by the rise and fall of the combustible gas pressure for closing and opening the supply of air and liquid fuel to the mixer and vaporizer, and a 10 throttle valve for regulating the supply of compressed air and combustible gas, one or both, to the engine.

11. In combination, an internal combustion engine, its valve chests, an air pump driven by the engine, an air and liquid fuel mixer and vaporizer, compressed air, liquid fuel, and combustible gas reservoirs, supply lines connecting the compressed air 15 reservoir with the air pump, the liquid fuel reservoir, the mixer and vaporizer and the valve chests and a supply line connecting the liquid fuel reservoir with the mixer and vaporizer and supply lines connecting the combustible gas reservoir with the mixer 20 and vaporizer and the valve chests.

12. In combination, an internal combustion engine, an air pump driven thereby, an air and liquid fuel mixer and vaporizer, compressed air, liquid fuel, and combustible 25 gas reservoirs, supply lines connecting the compressed air reservoir with the air pump, the liquid fuel reservoir, the mixer and vaporizer, and the engine and a supply line 30 connecting the liquid fuel reservoir with the mixer and vaporizer, supply lines connecting the combustible gas reservoir with the mixer and vaporizer, and the engine and a valve 35 controlled by the rise and fall of the combustible gas pressure to close and open the compressed air and liquid fuel supply lines 40 to the mixer and vaporizer and a throttle valve for opening and closing the compressed air and combustible gas supply lines 45 to the engine.

open the compressed air and liquid fuel supply lines to the mixer and vaporizer.

13. In combination, an internal combustion engine, an air pump driven thereby, an air and liquid fuel mixer and vaporizer, compressed air, liquid fuel, and combustible 50 gas reservoirs, supply lines connecting the compressed air reservoir with the air pump, the liquid fuel reservoir, the mixer and vaporizer and the engine and a supply line 55 connecting the liquid fuel reservoir with the mixer and vaporizer, supply lines connecting the combustible gas reservoir with the mixer and vaporizer and engine, and a throttle valve for opening and closing the compressed air and combustible gas supply lines to the engine.

14. In combination, an internal combustion engine, an air pump driven thereby, an air and liquid fuel mixer and vaporizer, compressed air, liquid fuel, and combustible 60 gas reservoirs, supply lines connecting the compressed air reservoir with the air pump, the liquid fuel reservoir, the mixer and vaporizer and the engine and a supply line 65 connecting the liquid fuel reservoir with the mixer and vaporizer, supply lines connecting the combustible gas reservoir with the mixer and vaporizer and the engine, a valve controlled by the rise and fall of the combustible gas pressure to close and open the compressed air and liquid fuel supply lines 70 to the mixer and vaporizer and a throttle valve for opening and closing the compressed air and combustible gas supply lines 75 to the engine.

In testimony, that I claim the foregoing as my invention, I have signed my name this 20th day of March, 1919.

PHILIP D. HIBNER.
